UNITED STATES PATENT OFFICE

94,526

DESIGN FOR A RUG

Alvah Tunnington, Springfield, Mass., assignor to Bigelow Sanford Carpet Co., Inc., a corporation of Massachusetts

Application November 9, 1934, Serial No. 53,955

Term of patent 3½ years

To all whom it may concern:

Be it known that I, Alvah Tunnington, a citizen of the United States, residing at Springfield, in Hampden County, and State of Massachusetts, have invented a new, original, and ornamental Design for a Rug, of which the following is a specification, reference being had to the accompanying drawing, forming part thereof.

The figure of the drawing is a face view of the quarter section of the rug, the dot and dash lines indicating the center point of the design. The unit of the design reverses at the center points as shown by the extensions beyond the centers.

I claim:

The ornamental design for a rug, substantially as shown and described.

ALVAH TUNNINGTON.
